(57) **CLAIM**

The ornamental design for a utility glove, as shown and described.

DESCRIPTION

FIG. 1 is a bottom view of a utility glove, according to the present design;

FIG. 2 is a top view thereof;

FIG. 3 is a left side view thereof; and,

FIG. 4 is a right side view thereof.

The broken lines in the figures illustrate environmental structure and form no part of the claimed design.
